UNITED STATES PATENT OFFICE.

CÉSAR FELIX JOSZ, OF BRUSSELS, BELGIUM.

METHOD OF ORNAMENTING PLATES.

SPECIFICATION forming part of Letters Patent No. 439,160, dated October 28, 1890.

Application filed September 25, 1889. Serial No. 325,065. (No specimens.) Patented in England July 15, 1889, No. 11,344; in Belgium January 25, 1890 No. 89,302; in Canada February 4, 1890, No. 33,568, and in Italy March 7, 1890, LIII, 37.

To all whom it may concern:

Be it known that I, CÉSAR FELIX JOSZ, a citizen of France, residing at No. 92 Boulevard Leopold II, Brussels, in the Kingdom of

5 Belgium, have invented a new and useful Improvement in the Manufacture of Ornamental Plates of Metal or other Malleable Sheets, (for which I have received Letters Patent in England, dated July 15, 1889, No. 11,344; in Bel-
10 gium, dated January 25, 1890, No. 89,302; in Canada, dated February 4, 1890, No. 33,568, and in Italy, dated March 7, 1890, Volume LIII, 37,) of which the following is a specification.

15 My invention relates to means of producing ornamental plates of metal or other malleable sheets—such as celluloid, papier-maché, or the like—by a process of grounding, printing, and, if desired, embossing, which I carry out as I will now describe. In the first place, in order 20 to vary the surface of the plate and render it suitable for receiving printed impressions, I render parts of it grounded or frosted while other parts of it remain smooth and polished in the following manner: I draw the pattern 25 of the frosted parts on a lithographic stone, which I ink with a varnish ink of an adhesive character. On this I sprinkle hard powder—such as sand, pulverized glass, emery, or the like—of various degrees of fineness, accord-
30 ing as I wish the frosting or grounding to be more or less fine. Removing from the stone all the powder except that which adheres to the inked parts of the design I press the plate on the stone, and thus I obtain the 35 frosting or grounding effect desired. After-
ward I print by ordinary printing any desired design on the plate, which is then var-
nished and dried in a stove.

When it is desired to emboss the plate, I pre-
40 pare a die and matrix in the following manner: I draw on a lithographic stone the design of the parts which are to be in relief and I etch out these parts with acid to the desired depth. I then take an impression of the 45 etched stone on somewhat soft material—such as lead, papier-maché, or the like—and having taken this impression, I trim by hand the edges and bodies of the relief parts of the impression, taking care to give the edges a lit-
50 tle slope.

Having thus prepared a die I glue over the etched stone a sheet of copper foil and by means of the die I press this sheet, causing it to enter the hollows of the etched stone, 55 but so as to form the counterpart form of

the trimmed die. I then by pressing the ornated plates between the die and matrix thus prepared give them the desired embossing.

Having thus described the nature of this 60 invention and the best means I know of carrying the same into practical effect, I claim—

1. The herein-described method of ornamenting plates, consisting in drawing a pattern on stone, inking the same with varnish 65 ink, sprinkling sand, emery, ground glass, or the like on said stone, then removing said sand, emery, or glass, except what adheres to the inked parts, and then pressing the plate to be ornamented on the stone, substantially 70 as set forth.

2. The herein-described method of ornamenting plates, consisting in drawing on stone the parts to be in relief, etching out these parts with acid, taking an impression of the 75 etched stone on soft material, then trimming the edges and bodies of the relief parts, then securing over the etched stone a sheet of copper-foil and by means of the die pressing it into the hollows of the said stone, and then 80 finally pressing the ornamented plate between the die and the matrix thus formed, substantially as set forth.

3. The herein-described method of ornamenting plates, consisting in drawing a pattern on stone, inking the same with varnish 85 ink, sprinkling sand, emery, ground glass, or the like on said stone, then removing said sand, emery, or glass, except what adheres to the inked parts, and then pressing the plate 90 to be ornamented on the stone, then drawing on stone the parts to be in relief, etching out these parts with acid, taking an impression of the etched stone on soft material, then trimming the edges and bodies of the relief parts, 95 then securing over the etched stone a sheet of copper-foil and by means of the die pressing it into the hollows of the said stone, and then finally pressing the ornamented plate between the die and the matrix thus formed, 100 substantially as set forth.

CÉSAR FELIX JOSZ.
